UNITED STATES PATENT OFFICE.

ALFRED E. HAGUE, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed March 4, 1924. Serial No. 696,776.

This invention relates to telephone systems wherein connections are established by means of mechanically controlled switches, and more particularly to such a telephone system wherein trunks are provided between a branch exchange and a central office.

In machine switching telephone systems heretofore devised with which the applicant is familiar, the link or trunk circuit between the branch exchange and the central office has not been made busy at the distant end until an appreciable interval of time has elapsed after its seizure at the originating end, often times resulting in double seizure of the same trunk resulting in considerable confusion. Another difficulty heretofore experienced has been that the busy condition was removed before the trunk circuit was fully restored to normal, hence if the trunk was again seized under such conditions, the new call would frequently fail to progress, and the old connection might not be fully broken down. Another difficulty experienced in existing machine switching systems has been that the false initiation of a call due to a trouble condition upon the connecting link or trunk circuit has caused one of a group of first link circuits (line switch or line finder, etc.,) to be seized and thus rendered unavailable to lines initiating regular calls. Another difficulty experienced in some machine switching systems is that after a call has progressed to a certain point, the switches are disconnected and the line returned to normal if the call fails to progress any further. If the call was falsely initiated by a trouble condition which (as usually occurs) was insufficient to cause it to progress properly, the call would again be initiated after the switches returned to normal and the switches would again be seized and again released. This cycle of operations usually termed "pumping" would continue until an attendant removed the cause of the trouble or put the defective line out of service.

The object of this invention is to so improve the circuits between the branch exchange and the central office as to eliminate the difficulties enumerated.

In accordance with this invention, a relay connected to the trunk circuit at the branch exchange causes the trunk to test busy immediately after it is seized at the central

office and to remain busy until the switches 55 at the central office are properly dismissed. Furthermore a combination of relays connected to the trunk at the central office prevents the connection from being built up unless the signals received from the branch exchange over the trunk conductors are the equivalent of those required to initiate a regular call, but in case the call was falsely initiated by a trouble condition will hold the defective trunk circuit in a locked condition, thus avoiding the trouble known as "pumping".

Fig. 1 diagrammatically represents the branch exchange end of a trunk circuit which is only accessible to dial stations, and 70 which is merely intended to be used for one way traffic (calls outgoing from the dial stations to the central office).

Fig. 2 diagrammatically represents the essential apparatus and circuits required at 75 the central office in a power drive system.

Fig. 3 diagrammatically represents the essential apparatus and circuits required at the central office in a step-by-step machine switching system such, for example, as the 80 Strowger type.

Fig. 4 diagrammatically represents the branch exchange end of a trunk circuit which is accessible either to the dial station or to the P. B. X. manual switchboard and 85 which is intended to be used for traffic in either direction, the calls incoming from the central office to the P. B. X. being handled by the operator at the P. B. X. manual switchboard.

The Strowger system and the power drive system are both so well known in the art that neither system will be described in full detail in this specification. Both systems are described very fully in the work entitled 95 "Automatic Telephony" by Smith and Campbell, second edition. The power drive system is likewise disclosed and described in the patent to Frank S. Irvine, No. 1,541,356, granted June 9, 1925, the patent to Franklin 100 A. Stearn, No. 1,505,571, granted August 19, 1924.

The invention may readily be adopted to other machine switching systems but as the two systems specifically referred to herein are typical, it is believed that the method of applying the invention to other systems will be readily discernible.

It is believed that the invention and its application will be fully understood from the detailed description which follows:

The invention may be used in a full mechanical step-by-step machine switch system in which case Fig. 3 will be used in conjunction with either Figs. 1 or 4. When two-way traffic is desired, Figs. 4 and 3 are used in combination and when one-way traffic only is required, Figs. 1 and 3 are used in combination.

Figs. 4 and 3 in combination.

Call from dial station to central office.—

When the receiver at the dial station 416 is removed from the switchhook and the dial 458 is operated in accordance with the digits comprising the central office code; the selectors S and S-1 are set extending the line from the calling station 416 to operate the relay 405 as follows: battery, winding of relay 405, 417, 451, 441, 431, 421, station 416, 420, 430, 440, 450, 418 to ground. Relay 405 operated, operates relay 412 over a circuit from battery, 426, 425, 424, 423, 419, winding of relay 412 to ground, and connects ground through the resistance 448 and winding of relay 401 to conductor 447 of the trunk, and solid ground to conductor 444 of the trunk for a purpose hereinafter described. Relay 412 operated, connects solid ground to the terminal 452 of the selector S-1 by way of conductor 434, to prevent the selector switches S and S-1 from releasing, and operates relay 411 over an obvious circuit. Relay 411 operated, operates the busy signal 410 and the relay 404 in parallel over obvious circuits. The signal 410 operated, indicates to the operator at the P. B. X. manual switchboard that the trunk with which the signal is associated is busy. Relay 404 operated, opens at 429 the conductor leading to the circuit of relay 407 to prevent it from operating falsely in case relay 403 should be momentarily operated.

Solid ground connected to the trunk conductor 444 closes a circuit to operate line relay 311, (Fig. 3) over a circuit as follows: battery, winding of relay 311, 329, 328, 327, 326, 325, 324, 323, 445, 444, 443, 439, 438, 437, 436, 435, to ground. Relay 311 operated, closes an obvious circuit to operate relay 310 through its lower winding. Relay 310 operated, causes the plunger 307 to plunge and close the leads connected to the various sets of springs 367, 306; 335, 336; 356, 355; to establish circuits which will hereinafter be more fully described. The operation of relay 310, opens at 329 the circuit for the line relay 311 but the latter being slow to release does not open the circuit through the lower winding of relay 310 until the circuit for the upper winding of the same relay has been established in a

manner hereinafter described. A circuit is now closed to operate relay 309 as follows: battery, winding of relay 309, 333, 334, 335, 336, 337, 338, 339, upper winding of relay 302, 343, 344, winding 312 of the dial tone transformer DT to ground. Relay 302 operates over a circuit as follows: battery, lower winding of relay 302, 353, 354, 355, 356, 357, 328, 327, 326, 325, 324, 323, 445, 444, 443, 439, 438, 437, 436, 435 to ground. Relay 302 operated, closes a circuit to operate relay 304 as follows: battery, winding of relay 304, 363, 359, 358, 303 to ground. Relay 304 operated closes the holding circuit for relay 310 heretofore referred to as follows: battery, upper winding of relay 310, 368, 306, 367, 366, 364, 365 to ground. This closure provides a substitute circuit to hold relay 310 operated after relay 311 releases. Relay 309 closes a testing circuit which if closed causes relay 300 to operate as follows: battery, winding of relay 300, 345, 346, 347, 348, 349, 446, 447, winding of relay 401, resistance 448, 438, 437, 436, 435, to ground. Relay 401 may or may not operate over this circuit depending upon the resistance of the trunk cable conductor 446 between the P. B. X. (Fig. 4) and the central office (Fig. 3). Relay 300 operated, locks through its own contact 345, and armature 369 by way of 368, 306, 367, 366, 364, 365 to ground; closes an obvious circuit to operate relay 305; connects solid ground to the sleeve terminal 319 associated with the trunk at the multiple bank of the connector C-1, causing the trunk to test busy to any connector which may be testing this trunk at the time; extends the circuit from the P. B. X. (Fig. 4) to the impulse relay 302 (Fig. 3) as hereinafter described. If the testing circuit traced is not closed due to a trouble condition on the trunk, relay 300 will not operate and the P. B. X. trunk circuit (Fig. 4) will not be linked to the impulse relay 302 of the selector circuit (Fig. 3) and the call cannot progress any further.

Relay 305 operated, opens at 333 the circuit through relay 309 which releases.

Having linked the trunk from the P. B. X. to the selector S-2, we are now ready to extend the connection through to the calling dial station 416 (Fig. 4) and to indicate to the station 416 that the circuit is in condition to dial the number of the called line which we will assume to be the station 318. It is first necessary to operate relay 400 and this is accomplished as hereinafter described. A circuit is now closed to operate relay 401 as follows: battery, lower winding of relay 302, 353, 354, 355, 356, 357, 328, 349, 446, 447, winding of relay 401, resistance 448, 438, 437, 436, 435 to ground. Relay 401 operated, closes an obvious circuit to operate relay 402 which in turn closes another obvious circuit to operate relay 406.

Relays 400 and 408 operate in parallel over obvious circuits when relay 406 operates. Relay 408 operated, locks by way of its contact 453, and conductor 454 under control 5 of relay 411; and at 435 removes the ground from conductor 436 and the trunk conductors 444 and 447. Relay 400 operated, completes the connection between the calling station 416 (Fig. 4) and the selector S-2 10 (Fig. 3); opens the circuit through relay 405 which releases; provides at its armature 455 a substitute path to hold the relay 412 operated after relay 405 releases.

With the connection established between 15 the calling station 416 and the selector S-2, the impulse relay 302 is connected in series with the calling line in the usual manner and the interrupted current produced in the winding 373 of the dial tone transformer 20 DT (from a source not shown) induces a similar current in its winding 312 which is in series with the calling station 416. This interrupted current produces a tone in the receiver of the calling station 416 as an indication that the circuit is in condition for 25 dialing.

When the dial 458 of the calling station 416 (Fig. 4) is operated and released, the circuit at the calling station 416 is interrupted and the impulses thus produced are transmitted to impulse relay 302 (Fig. 3) which follows the impulses. Each time relay 302 releases a circuit is closed to operate primary magnet 317 over a circuit as follows: battery, winding of primary magnet 317, winding of relay 308, 375, 374, 376, 359, 358, 303 to ground. Brushes 320 to 322, inclusive, are moved by successive steps in accordance with the primary movement 40 of the selector S-2. During the first step of the brushes 320 to 322, inclusive, the off-normal contacts ON are closed. Relay 308 operates in series with the primary magnet 317 the first time the impulse relay 302 releases but relay 308 being slow to release remains operated throughout the impulse period.

As soon as the off-normal contacts ON are closed a circuit is closed to operate relay 315 as follows: battery, winding of relay 315, 377, 378, 379, 364, 365, to ground. Relay 315 operated, locks as follows: battery, winding of relay 315, 377, 382, 383, 358, 303 to ground. The primary movement 55 of the switch is completed at the end of the impulse train and the impulse relay 302 remains operated opening the circuit through the primary magnet 317 and relay 308, releasing the magnet and the relay. In releasing, relay 308 closes a circuit to operate the secondary magnet 314 as follows: battery, winding of secondary magnet 314, 384, 380, 379, 364, 365 to ground. The operation of the secondary magnet initiates the secondary 60 movement of the selector switch S-2 causing

the brushes 320 to 322, inclusive, to advance one step to the terminals of the first trunk of the selected group. The secondary magnet 314 in operating opens at its contact 382 the locking circuit for relay 315 previously traced releasing relay 315. If the first trunk is busy, solid ground on the sleeve terminal (corresponding to the terminal 332) will be connected to the brush 322. The release of relay 315 opens the operating circuit (previously traced) of the secondary magnet 314 which likewise releases. A circuit will now be closed by way of the sleeve terminal of the busy trunk to reoperate relay as follows: battery, winding of relay 315, 377, 382, 385, 386, 387, 388, 322, terminal corresponding to 332, to ground. Relay 315 operated, locks over the locking circuit previously traced and closes the circuit previously traced for the secondary magnet 314. 70 The secondary magnet 314 again operates, advances the brushes 320 to 322 to the terminals of the next trunk in the group and again opens at 382 the locking circuit for the relay 315, releasing the relay which in turn opens the circuit through the secondary magnet 314 which likewise releases. A circuit will now be closed by way of the sleeve terminal of the busy trunk to reoperate relay as follows: battery, winding of relay 315, 377, 382, 385, 386, 387, 388, 322, terminal corresponding to 332, to ground. Relay 315 operated, locks over the locking circuit previously traced and closes the circuit previously traced for the secondary magnet 314. 80 The secondary magnet 314 again operates, advances the brushes 320 to 322 to the terminals of the next trunk in the group and again opens at 382 the locking circuit for the relay 315, releasing the relay which in turn opens the circuit through the secondary magnet 314 which likewise releases. A circuit will now be closed by way of the sleeve terminal of the busy trunk to reoperate relay as follows: battery, winding of relay 315, 377, 382, 385, 386, 387, 388, 322, terminal corresponding to 332, to ground. Relay 315 operated, locks over the locking circuit previously traced and closes the circuit previously traced for the secondary magnet 314. 85 The secondary magnet 314 again operates, advances the brushes 320 to 322 to the terminals of the next trunk in the group and again opens at 382 the locking circuit for the relay 315, releasing the relay which in turn opens the circuit through the secondary magnet 314 which likewise releases. A circuit will now be closed by way of the sleeve terminal of the busy trunk to reoperate relay as follows: battery, winding of relay 315, 377, 382, 385, 386, 387, 388, 322, terminal corresponding to 332, to ground. Relay 315 operated, locks over the locking circuit previously traced and closes the circuit previously traced for the secondary magnet 314. 90 The secondary magnet 314 again operates, advances the brushes 320 to 322 to the terminals of the next trunk in the group and again opens at 382 the locking circuit for the relay 315, releasing the relay which in turn opens the circuit through the secondary magnet 314 which likewise releases. This cycle of operations continues until an idle trunk is found.

Let us assume that the brushes 320 to 322, inclusive, are now resting upon the terminals 330 to 332, inclusive and that the selector switch S-3 is idle in which case the terminal 332 will be free from ground. A circuit will now be closed to operate the relay 301 as follows: battery winding of relay 315, 377, 382, 385, winding of relay 301, 366, 364, 365 to ground. Relay 315 will not operate at this time due to the high resistance of the winding of relay 301 in series with it. Relay 301 operated, extends the connection by way of the brushes 320 to 322, inclusive, to the selector switch S-3. The impulse relay, not shown, of the selector switch S-3 will operate, operating a slow relay, not shown, in the selector switch S-3 which will cause solid ground to be connected to the terminal 332. The relay 301 operated opens at 339 and 353 the circuit through the impulse relay 302 which releases and in turn opens the circuit through relay 304. Relay 304 being slow to release, does not release immediately but remains operated long enough for the slow relay, not shown, in the selector switch S-3 to operate and connect ground to the terminal 332. Relay 301 now locks over the following circuit: battery, winding of relay 315, 377, 382, 385, winding of relay 301, 390, 387, 388, 322, 332 to ground (not shown) in the selector S-3. Relay 310 locks to ground by way of terminal 332, 388, 387, and 390 under control of relay 301. The selector switch S-3 operates under control of the dial 458 of the calling station 416 in substantially the same 100 105 110 115 120 125 130

manner as the selector switch S-2, and extends the connection to the connector C which likewise operates under control of the dial 458 of the calling station 416 to complete the connection to the called station 318.

The called station 318 is signaled in a manner not shown, and upon responding establishes the talking circuit between the calling and called stations. Battery to maintain the relay 401 (Fig. 4) operated is supplied by the connector C in a manner not shown.

Holding.—So long as the talking circuit is established and the loop is closed at station 416, the impulse relay (not shown) in the connection C and the relay 401 remain operated in series. So long as the impulse relay in the connector remains operated the switches cannot release. Relay 401 holds relay 402, which in turn holds relay 406. Relay 406 holds relay 400, which in turn, holds relay 412, the latter maintaining relay 411 operated. The busy condition is accordingly maintained at terminal 452 of the selector S-1, at the terminal 319 of the connector bank C-1, and the busy signal 410 at the manual switchboard likewise remains operated. Thus, intrusion upon the connection either at the terminal bank of the selector S-1 (Fig. 4), or the connector bank C-1 (Fig. 3), or at the jack 414 in the manual switchboard (M. S. B. Fig. 4) is prevented.

Flashing.—Should the calling station 416 momentarily operate the switchhook, relay 401 will release, in turn releasing relay 402, which in turn opens the circuit to release relay 406. Meanwhile the release of the switchhook at the calling station 416 causes relay 401 to reoperate, reoperating relay 402. Relays 402 and 406 are designed to be slow to release to prevent relay 406 from releasing when the switchhook is thus momentarily depressed.

Disconnect.—When the receiver is replaced on the switchhook at the calling station 416, relay 401 will release in turn releasing relay 402 which in turn releases relay 406. The release of relay 406 opens the circuit through relay 400 which releases, thus opening (at 470 and 471) the talking circuit previously established between the calling and called stations. Relay 409 is now connected (at 472 and 473) in bridge across the conductors 444 and 447 of the trunk operating relay 409. Relay 409 operated, furnishes a substitute holding path to prevent relay 412 from releasing when the battery, supplied at armature 455, is removed by the release of relay 400. Relay 412 is designed to be slow to release so that it will remain operated while one holding circuit is being opened and another is being substituted therefor.

65 So long as relay 409 remains operated,

relay 412 will remain operated, consequently the calling station will remain locked to the trunk circuit by way of the selector switches S and S-1 and the busy signal 410 will continue to be displayed before the operator at 70 the manual switchboard (Fig. 4). Relay 409 remains operated in series with the impulse relay (not shown) of the connector circuit C (Fig. 3); but due to the high resistance of relay 409, the impulse relay in 75 the connector circuit C releases, releasing the connector switch C in a manner which is so well known in the art that it is not shown in the drawing and will not be described in detail here. The release of the connector C removes battery from the conductors 445 and 446 (Fig. 4) and ground from the terminal 352 of the selector S-3 (Fig. 3).

Removing battery from the conductors 85 445 and 446 releases relay 409 opening the circuit through relay 412 which in turn releases. Relay 412 released, opens the circuit for relay 411 which releases. Relay 411 released, opens the circuits for the busy signal 410 and the relay 404, releasing relay 404 and restoring the busy signal to normal at the manual switchboard. In order to retain the busy condition at the sleeve terminal 452 of the selector S-1 as long as possible ground is connected to the conductor 434 by way of 460 and 461 after relay 412 releases and as long as relay 411 remains operated. The release of relay 411 removes ground from the conductor 434 allowing 100 the selectors S and S-1 to release and restore to normal.

When the ground was removed from the terminal 352, the selector switch S-3 was restored to normal in a manner not shown. 105 At the same time, the circuits for relays 301 and 310 of the selector S-2 were opened, releasing these relays. The release of relay 310 causes the plunger 307 to release, separating the various pairs of contacts 367 and 306; 335 and 336; and 356 and 355. The release of relay 301 closes a circuit to operate the release magnet 316 as follows: battery, winding of release magnet 316, 381, 304, 376, 359, 358, 303 to ground. The release magnet operates causing the rod of the selector switch S-2 to restore to normal. With the switch in the normal position contacts ON are separated opening the circuit through the release magnet 316 which releases thus fully restoring the circuit to normal.

All trunks busy.—If all the trunks in the group had been busy at the time the selector S-2 was hunting for an idle trunk, the brushes 320 to 322, inclusive, would have stepped from trunk to trunk until they arrived in the all trunks busy or eleventh step position (assuming the trunk group to consist of ten trunks). With the switch in this 130

position the trunks busy contacts TB would be operated thus opening at 343 and 344 the conductor to the winding 312 of the dial tone transformer DT and closing at 343 and 5 391 the conductor leading the winding 313 of the busy tone transformer BT. This change in the condition of the circuit changes the character of the tone produced 10 in the telephone receiver at the calling station 416, from what is known as a dial tone to a busy tone, which the subscriber at the station 416 will readily recognize and whereupon the receiver of the calling station 416 would be replaced on the switchhook restoring the circuit to normal in the manner 15 previously described.

Pumping of sender.—If the system were arranged so that when relay 309 operated as described under "Call from dial station to central office" a local circuit was closed to operate relay 300 instead of the circuit including the trunk conductors 446 and 447 and the resistance 448, then relay 300 would have extended the trunk to the impulse relay 25 302 in the manner previously described. Relay 302, however, will not remain operated at this time unless either ground is now present upon conductor 349 or a loop circuit is present across the conductors 323 and 349. 30 If neither of these circuit conditions is present, relay 302 releases in turn releasing slow-to-release relay 304 which in turn releases relay 310. The release of relay 310 releases the line switch and any other relays 35 which are operated also release, restoring the selector switch S-2 (Fig. 3) to normal. When the selector is restored to normal, the circuit to operate relay 311 is again closed over trunk conductor 323 in the manner previously described and the cycle of operations 40 is repeated. The cycle of operations described is known as "pumping the sender".

Call from P. B. X manual switch board to central office.—When the plug of a cord 45 circuit (not shown) is inserted in the jack at the manual switch board M. S. B. relay 411 is operated over an obvious circuit to ground at the contact 415 of the trunk jack. Relay 411 operated, connects ground at 460 to the test terminal 452 of the selector S-1 by way of the conductor 434 causing the trunk circuit to test busy at the selector multiple bank. Relay 404 and the busy signal 410 are operated in parallel over obvious circuits; 50 the latter indicating at the manual switch board that the trunk is busy. The cord circuit (not shown) is provided with a bridge which loops the jack springs 462 and 463 together. A circuit is now closed to operate relay 405 as follows: battery, winding of relay 405, 417, 464, 465, 463, through the bridge in the cord circuit (not shown) 462, 466, 418 to ground. Relay 405 operated, closes a circuit to operate relay 412 and from this point 55 on the circuit functions in the manner pre-

viously described under "Call from dial station to central office".

Flashing.—The operator at the manual switchboard may withdraw the plug of the cord from the trunk jack momentarily in 70 which case the circuit functions in the manner previously described under "Flashing" in "Call from dial station to central office".

Disconnect.—When the plug of the cord is removed from the trunk jack (Fig. 4) at the 75 manual switchboard, disconnection takes place in the general manner previously described under "Disconnect"—"Call from dial station to central office".

Call incoming from central office to P. B. 80 X. manual switchboard.—On an incoming call (either local or toll) from the central office, a connector circuit (not shown) establishes connection with the terminals indicated at C-1 (Fig. 3), closing a circuit by 85 way of the test terminal 319 to operate relay 305. Relay 305 operated, prevents any of the relays associated with the line switch circuit from operating, thus avoiding any possibility of a false connection with a selector 90 switch such as S-2. With a connector circuit connected to the terminals C-1, a circuit is closed by way of leads 445 and 446 to operate the relay 409 which is at this time bridged across the trunk conductors 444 and 95 447. Relay 409 operated, closes an obvious circuit to operate relay 412 which in turn closes another obvious circuit to operate relay 411. Relay 412 operated, also connects solid ground by way of the conductor 434 to 100 the test terminal 452 of the selector switch S-1, causing the trunk circuit to test busy immediately at the selector multiple bank (Fig. 4). Relay 411 operated, operates relay 404 and the busy signal 410 in parallel 105 over obvious circuits, the latter indicating to the operator at the manual switchboard that the trunk is busy.

In case the call is incoming from some local point, signaling will take place immediately the connector (not shown) establishes connection with the terminals C-1. If, however, the call is incoming from a toll office, signaling will not commence until after the toll operator has received the proper ringing signal which will not occur until the circuit for signaling the manual switchboard is fully established. It is necessary, however, to cause the trunk to test busy both at the manual switchboard and at the multiple 115 bank of the selector S-1 (Fig. 4) immediately the trunk is seized by the connector at the terminals C-1, to prevent the possibility of a false trunk seizure. This is accomplished in the manner already described. When 120 signaling current is applied to the trunk by way of the connector circuit (not shown) relay 403 which is bridged in series with condenser 459 across the trunk conductors 444 and 447 operates, opening the circuit through 125 130

relay 404 which releases closing the circuit to operate relay 407 traced for convenience as follows: ground, winding of relay 407, 429, 467, 468, 454, 428, 427, to battery. Relay 407 locks under control of relay 406 and closes at its contact 469 an obvious circuit to light the trunk lamp 413 as a calling signal. Relay 407 operated, opens the circuit for relay 409 which releases, but relay 412 which was previously operated under control of relay 409 does not release as a substitute holding path is furnished by way of conductor 419 and contact 470 of relay 407.

Upon observing the lighted line lamp, the operator at the manual switchboard inserts the plug of a cord (not shown) into the trunk jack closing at its contact 415 a substitute holding path for relay 411. The relay 405 now operates in series with the bridge 20 of the cord circuit (not shown) in the manner previously described in "Call from P. B. X. manual switchboard to central office". Relay 405 operated, connects the resistance 448 in bridge across the conductors 444 and 447 of the trunk, in order to remove automatic ringing (where used) from, and to operate the supervisory relay in, the connector circuit (not shown) (Fig. 3). Relay 401 operates in series with the resistance 448 30 from battery furnished from the connector switch (not shown) (Fig. 3). Relay 401 operated, operates relay 402 over an obvious circuit which in turn closes another obvious circuit to operate relay 406. Relay 406 operated, opens the locking circuit for relay 407 which releases, and closes an obvious circuit to operate relay 400. Relay 407 released, extinguishes the line lamp 413. Relay 400 operated, establishes the talking circuit between the central office and the manual switchboard and opens the circuit through relay 405 which releases.

From this point the circuit functions in the manner previously described under "Call 45 from dial station to central office".

Figs. 1 and 3 in combination.—Figs. 1 and 3 may be used in conjunction where it is only desired to have traffic in one direction, namely, from the dial station at the P. B. X. to 50 the central office.

When Figs. 1 and 3 are thus used in conjunction, removing the receiver at the calling station 115 (Fig. 1) operates a line switch (not shown) to extend the calling 55 line to the selector switch S-4. The necessary central office code is dialed at the calling station 115 and the selector switches S-4 and S-5 are set to extend the calling line to the outgoing trunk circuit shown in Fig. 1.

With the switches thus set, a circuit is closed to operate relay 100 in series with the calling line. Relay 100 operated closes an obvious circuit to operate relay 102; connects solid ground at 108 to the conductor 109, 60 and ground through the resistance 107 and

winding of 106 to the conductor 119. The line relay 311 (Fig. 3) now operates by way of conductors 323 and 109 to ground at 108 under the control of relay 103. The operation of relay 102 connects solid ground to 70 the test terminal 142 of the selector S-5 to prevent the selector switches S-4 and S-5 from releasing and to cause the trunk circuit (Fig. 1) to test busy to all other selector switches. Relay 311 operated, operates relay 310 through its lower winding over an obvious circuit causing the plunger 307 to plunge and extend the circuit to the selector switch S-2. Relay 309 now operates in series with the upper winding of relay 302. Relay 302 75 operates through its lower winding via conductors 323 and 109 to solid ground at 108 under the control of relay 103. Relay 302 operated, closes an obvious circuit to operate relay 304. Relay 309 operated, closes a circuit to operate relay 300 by way of 345, 346, 347, 348, 349 and 119, relay 106, resistance 107, 108 to ground. Relay 300 operated, locks at 369 to ground at 365 under control of relay 304. Relay 106 may operate in series with relay 300 but will operate in series with relay 302 after relay 300 operates and extends the trunk circuit (Fig. 1) to the selector switch S-2. The operation of relay 106 operates relay 104 over an obvious circuit. Relay 104 operated, closes obvious parallel circuits to operate relays 101 and 103. Relay 103 operated, locks under control of relay 102 and removes ground at its armature 108 from the trunk conductors 109 and 119. Relay 101 operated, extends the calling line by way of the outgoing trunk circuit (Fig. 1) to the selector switch S-2; provides a substitute path to hold the relay 102 operated after relay 100 releases; 105 opens the circuit through relay 100 which releases removing the shunt formed by the resistance 107 from across the conductors 109 and 119. The dial at the calling station 115 is now operated and released in accordance with the digits of the number of the called line 318 (Fig. 3) and the selector switches S-2 and S-3 and the connector C are set to extend the connection to the called line in the manner previously described under "Figs. 4 and 3 in combination."

The called line 318 is signaled in a manner not shown, and upon responding, the talking connection is established.

Flashing.—When the calling station 115 flashes, relay 106 releases, opening the circuit through relay 104, but the latter which is designed to be slow to release, remains operated until relay 106 reoperates, when the switchhook at the calling station 416 is again released.

Disconnect.—When the receiver is replaced on the switchhook at the calling station 115, relay 106 releases, opening the circuit through relay 104 which releases, in 130

turn, releasing relay 101. Relay 105 is now connected in bridge with the conductors 109 and 119 by way of armature 117 of relay 101. Relay 105 operates in series with the impulse relay (not shown) in the connector C, thus providing a substitute path to keep relay 102 from releasing when relay 101 releases. Relay 102 is designed to be slow to release, so that it will not release immediately in case its holding circuit is momentarily opened, while a substitute circuit is being provided to keep it operated. Relay 102, accordingly, remains operated, preventing the selector switches S-4 and S-5 from releasing and maintaining the busy condition on the test terminal 142 of the selector S-5.

The impulse relay (not shown) in the connector circuit C (Fig. 3) will release due to the high resistance of the winding of relay 105 (Fig. 1) in series with it. The release of the impulse relay allows the connector C to release and restore to normal in a manner not shown. The selector switches S-2 and S-3 now release in the manner previously described. When the connector C releases, the circuit through relay 105 is opened and this relay releases. Relay 105 released, opens the circuit through relay 102 which releases, removing the holding ground from the test terminal 142 of the selector switch S-5 and allowing the selector switches S-4 and S-5 to release and restore the circuit to normal.

The invention may also be used in conjunction with a full mechanical power driven machine switching system, in which case Fig. 2 will be used in conjunction with either Fig. 1 or Fig. 4. When two way traffic is desirable, Figs. 4 and 2 are used in combination and when only one way traffic is required, Figs. 1 and 2 are used in combination.

Figs. 4 and 2 in combination.

Call from dial station to central office.—When the receiver at the dial station 416 is removed from the switchhook and the dial 458 is operated in accordance with the digits comprising the central office code, the selectors S and S-1 are set extending the line from the calling station 416 to the relay 405, and the outgoing trunk circuit (Fig. 4) functions in the general manner previously described under "Figs. 4 and 3 in combination". The connection is now extended over the trunk conductors 445 and 446 to the circuit shown in Fig. 2 and relay 206 operates over a circuit as follows: battery, winding of relay 206, 246, 236, 238, 237, 233, 445, 444, 443, 439, 438, 437, 436, 435 to ground. Relay 206 operated closes a circuit (not shown) in the line finder LF causing the brushes 240 to 242, inclusive, of the line finder LF to hunt for the calling line. When the brush 242 engages with the terminal 232 of the

calling line, a circuit is closed to operate relay 202 by way of brush 242 and terminal 232. The line finder is set upon the terminals 230 to 232 of the calling line in a manner not shown herein, but which is fully described in the patent to Frank S. Irvine, No. 1,541,356, granted June 9, 1925, and the patent to Franklin A. Stearn, No. 1,505,571, granted Aug. 19, 1924. Relay 202 operated, opens at 246 the circuit through relay 206 which releases. With the brush 242 of the line finder switch LF connected to the terminal 232 of the calling trunk, a busy condition is provided at the test terminal 220 of the final multiple FM by way of 243 and 244 to prevent the calling trunk from being seized by a switch at the final multiple FM, during the progress of a call incoming from the central office to the P. B. X. (Fig. 4). A circuit controlled by the line finder LF and district selector DS is now closed to operate the sender selector SS (in a manner not shown but fully described in the art cited), causing the sender selector SS to hunt for and link an idle register sender to the line finder LF and district selector DS, (in a manner not shown and which forms no part of the invention herein disclosed but which is fully described in the art cited). Let us assume that the sender selector SS, (Fig. 2) links the register sender RS with the line finder LF and the district selector DS, in which case brushes 250 to 253 inclusive will be set upon the terminals 260 to 263 inclusive as shown in the drawing (Fig. 2).

An obvious circuit is now closed to operate relay 211 by way of terminal 262 and brush 252. Relay 211 operated, connects ground by way of its armature 254, lead 255, terminal 256, and brush 217 to the motor magnet 208 which operates opening at its armature 257 the operating circuit traced and causing the motor magnet 208 to release. The release of the motor magnet 208 causes the brushes 217 to 219, inclusive, to rotate one step in a clockwise direction over a terminal in each of the arcs 214 to 216, inclusive. With the motor magnet released and the brush 217 at rest upon the next terminal of the arc the operating circuit for the motor magnet 208 is again closed and the cycle of operations is repeated, and provided relay 211 remains operated, the brushes 217 to 219 inclusive, will continue to rotate until the brush 217 rests upon the terminal 258 of the arc 214 when the operating circuit for the motor magnet 208 is opened. When the register sender RS is linked to the line finder LF circuits are closed to operate relay 201 by way of its right winding in series with relay 207, and to operate relay 210 over a circuit as follows: battery, winding of the impulse relay 210, 260, 250, 241, 231, 236, 238, 237, 233, 445, 444, 443, 439, 438, 437, 120

436, 435 to ground. Relay 210 operated, closes an obvious circuit to operate relay 209. Relay 201 operated, closes an obvious circuit to operate relay 205 maintaining a 5 busy condition on the test terminal 220 at the final multiple FM by way of 243, 245, 247 and 248. Relay 201 now locks through its left hand winding by way of 258 and 259 to battery at brush 242 of the line finder 10 LF. A circuit is now closed to operate relay 200 as follows: battery, winding of relay 200, 223, 224, 225, 226, 234, 446, 447, winding of relay 401, 448, 438, 437, 436, 435 to ground. Relay 200 operated, locks 15 by way of its armature 227 under control of relay 205. The relays in the outgoing trunk circuit (Fig. 4) now function in the manner previously described under "Figs. 4 and 3 in combination" and the calling line 416 is 20 extended by way of the trunk conductors 444 and 447; 445 and 446; 233 and 234; 235 and 236 to the impulse relay 210 and the relay 207. The calling station 416 is now 25 in series with relays 210 and 207, and may now control the impulse relay 210 by means of the dial 458. The dial 458 is operated in accordance with the various digits of the number of the called line 213 and the various trains of impulses produced by the dial 458 30 cause the impulse relay 210 to release and re-operate in unison therewith. Each time relay 210 releases, a circuit is closed over the impulse lead 228 by way of 229, 264, 265 and 266 to ground. The registers (not 35 shown) are set in sequence by way of the impulse lead 228 under control of the impulse relay 210. The method of registering the impulses produced by the dial 458, of setting the switches DS, IS, and FS (Fig. 40 2) and of signaling the called line 213 forms no part of this invention and will not be described herein. A complete explanation regarding the method of accomplishing these functions is given in the art cited.

45 *Dismissing the sender.*—When selection has been completed the circuit through relay 211 is opened in a manner not shown but which is fully described in the art cited and relay 211 releases, closing by way of its armature 254, lead 249 and brush 218, a circuit to operate the motor magnet 208 which is thus restored to normal. The circuit through the impulse relay 210 is likewise 50 opened in a manner not shown, releasing relay 210, which in turn releases relay 209. A circuit is now closed in a manner not shown but fully described in the art cited, causing the sender selector SS to function and restore to normal.

55 The talking circuit is now established and remains established as long as the receivers at the calling and called stations, 416 and 213, remain off the switchhooks.

60 *Flashing.*—When the calling station 416 flashes, the outgoing trunk circuit (Fig. 4)

functions in the manner previously described under "Flashing" ("Figs. 4 and 3 in combination").

Disconnect.—When the calling station 416 disconnects the outgoing trunk circuit (Fig. 4) 70 functions in the general manner previously described under "Disconnect" ("Figs. 4 and 3 in combination") and relay 409 operates in the usual manner to prevent the selector switches S and S-1 from releasing. The selector switches DS, IS, and FS, and the line finder LF release, removing battery from the trunk conductors 445 and 446 allowing relay 409 to release. After relay 409 75 releases, the selector switches S and S-1 and the outgoing trunk circuit (Fig. 4) restore to normal in the manner previously described.

Call from P. B. X. manual switchboard to central office.—The outgoing trunk circuit (Fig. 4) 80 functions in the general manner previously described on a "Call from P. B. X. manual switchboard to central office" ("Figs. 4 and 3 in combination"). The circuit shown in Fig. 2 functions in the general 85 manner previously described under "Call from dial station to central office" ("Figs. 4 and 2 in combination").

Call incoming from central office to P. B. X. manual switchboard.—The circuit 90 functions in the general manner previously described under "Call incoming from central office to P. B. X. manual switchboard" 95 ("Figs. 4 and 3 in combination").

Figs. 1 and 2 in combination.

When only one way traffic (from the dial station to the central office) is required, Fig. 2 is used in conjunction with Fig. 1. Fig. 1 100 functions in the manner previously described under "Figs. 1 and 3 in combination". Fig. 2 functions in the general manner previously described under "Figs. 4 and 2 in combination".

It is evident from the preceding description that the progress of any call from the P. B. X. to the central office may be divided into stages as follows:

1. Initiating a call connects ground to both sides of the trunk and makes the circuit 110 busy at the P. B. X.

2. The line relay at the central office is operated over one trunk conductor and an idle mechanical switch is seized.

3. When the mechanical switch has been 120 found by the trunk circuit, the latter is made busy at the central office and a test circuit is connected to the other trunk conductor to test the trunk circuit and the switching mechanisms simultaneously before the calling line and switching mechanisms are linked together.

4. If the trunk circuit and switching mechanism test closed the connection is extended, and the calling line and the switch- 125

ing mechanism are connected to the trunk in preparation for dialing, but if the circuits heretofore referred to do not test closed the circuits remain locked in the condition they have assumed and the call does not progress any further.

5. When the P. B. X. disconnects at the end of a regular call, a hold busy circuit is closed which keeps the trunk busy and locks the selector switches to the trunk circuit at the P. B. X. until the connection is cleared out at the central office when the hold busy circuit is opened and the P. B. X. circuits are restored to normal.
10. 6. The switching mechanism at central office is able to distinguish between a hold busy circuit for talking condition, and a hold busy circuit release condition so that it will hold on the former and release on the latter.

It is also evident that on a call from the central office to the P. B. X. the hold busy circuit is closed immediately the trunk is seized so that the trunk is caused to test busy immediately at all points of access at the P. B. X., even before the P. B. X. is signaled or otherwise informed that a call incoming from the central office is in waiting.

30. When reverse battery supervision is used relay 105, (Fig. 1), or 409 (Fig. 4) as the case may be, should be of the polarized type.

What is claimed is:

35. 1. In a machine switching telephone system, a calling line, a trunk circuit, switching mechanism at either end thereof operable in association therewith under control of the calling line, means at each end of the trunk for indicating when it is busy, means including a relay bridged across the trunk at the end adjacent to the calling line for holding the trunk busy thereat after the calling line disconnects while permitting the switching mechanism at the distant end of the trunk to release, and means controlled by said bridging relay for thereafter releasing the remaining switching mechanism and removing the busy condition from the trunk.
40. 2. In a machine switching telephone system, a first office, a calling line thereat, a second office, a called line therein, a trunk circuit between the first and second offices, means including one or more automatic switches in the first office operable under control of the calling line for linking the calling line to the trunk circuit, means including one or more automatic switches in the second office operable over the trunk circuit under control of the calling line to build up a connection to the called line, means for causing the trunk circuit to test busy at either end, means for releasing the switches at the second office when the calling line disconnects, means effective when the calling

line disconnects for maintaining the busy condition on the trunk circuit at the first office until after the switches at the second office have been released, and means at the first office for releasing the switches and removing the busy test from the trunk circuit after the switches at the second office have been released.

3. In a machine switching telephone system, a first office, a calling line thereat, a second office, a called line therein, a trunk circuit between the first and second offices, means including one or more automatic switches in the first office operable under control of the calling line for linking the calling line to the trunk circuit, means including one or more automatic switches in the second office operable over the trunk circuit under control of the calling line to build up a connection to the called line, means for causing the trunk circuit to test busy at either end, means for allowing the switches in the second office to release when the calling line disconnects while retaining the busy condition upon the trunk at the first office, and means effective when the switches in the second office have been released for restoring the trunk circuit to normal in the first office.

4. In a machine switching telephone system, a switching mechanism, a trunk circuit accessible thereto, means controlled by the trunk circuit for seizing the switching mechanism, and means included in the trunk circuit for testing both the trunk circuit and the switching mechanism before extending the trunk conductors to the switching mechanism.

5. In a machine switching telephone system, a switch, a trunk circuit, means controlled by the trunk circuit for seizing the switch and a testing device included in the trunk circuit for testing both the trunk circuit and the switch before linking them together.

6. In a machine switching telephone system, a switch, a trunk circuit, means controlled by the trunk circuit for seizing the switch, a testing device included in the trunk circuit for testing both the trunk circuit and the switch, and means including the testing device for preventing the trunk circuit and switch from being linked together unless the proper test conditions are encountered on each.

7. In a machine switching telephone system, a calling line, a trunk circuit, an automatic switch, means controlled by the calling line for linking the line to the switch, means controlled by the calling line for causing the switch to seize the trunk circuit, a distant switch to which the trunk has access, means in the trunk circuit controlled by the calling line for causing the trunk circuit to seize the distant switch, and

a testing device included in the trunk circuit for testing both the trunk circuit and the distant switch before the calling line, trunk circuit and distant switch are linked together.

8. In a machine switching telephone system, a switch, a trunk circuit accessible thereto, means in the trunk circuit for seizing the switch, and means in the trunk circuit for preventing the pumping of the switch when the trunk is caused to seize it due to the existence of a trouble condition on the trunk.

9. In a machine switching telephone system, a calling line, a called line, a two conductor trunk circuit having a plurality of points of access, mechanical switches operable under control of said calling line to seize said trunk circuit at one point of access, another mechanical switch, means responsive to the extending of said calling line to said trunk for seizing said last mentioned switch, means operable under control of said calling line to set said last mentioned switch to build up a connection to said called line, means at each end of the trunk responsive to said trunk seizure for causing said trunk to test busy at every point of access, means responsive to the opening of the calling line circuit for initiating the breaking down of the connection by releasing said last mentioned switch and means responsive to said breaking down operation for releasing the remaining mechanical switches and for restoring said trunk circuit to normal.

10. In a telephone system, a two-conductor trunk, switch mechanism at either end thereof capable of seizing the said trunk, means at one end of said trunk operable in response to the seizure of said trunk at the opposite end over a circuit including only one conductor of the trunk for rendering the trunk busy at said first mentioned end, and means at the other end of the trunk operable in response to seizure of the trunk at the opposite end over a circuit including both of the conductors for rendering said trunk busy at said other end.

11. In a telephone system, a two-conductor trunk, switch mechanism at either end thereof capable of seizing said trunk, means including a relay at one end of said trunk operable in response to the seizure of said trunk at the opposite end over a circuit including only one conductor of the trunk for rendering the trunk busy at said first mentioned end, and means including a relay at the other end of the trunk operable in response to the seizure of the trunk at the opposite end over a circuit including both of the trunk conductors for rendering said trunk busy at said other end.

12. In a telephone system, a calling line, a two-conductor trunk, switch mechanism at either end thereof operable under control of the calling line for seizing said trunk at a point at one end and for extending said trunk at a point at the opposite end, other points of access at both ends of said trunk whereat said trunk may be seized, means operable over a circuit including one trunk conductor in response to the seizure of said trunk by the calling line at one end and extension of the trunk at the opposite end for rendering the trunk busy at the points of access at said opposite end, and means responsive only to said seizure of the trunk for rendering the trunk at the points at the first mentioned end busy.

13. In a telephone system, a two-conductor trunk, mechanical switches at either end thereof capable of seizing said trunk, another mechanical switch adapted for extending said trunk at one point after it has been seized at another point, and means responsive to the seizure of said trunk at one point for rendering said trunk busy at certain points of access and responsive to the extension of said trunk through said second mentioned switch for rendering said trunk busy at other points of access.

In witness whereof, I hereunto subscribe my name this 29th day of February A. D., 1924.

ALFRED E. HAGUE
